HYDRAULIC HOIST FOR LADDERS

Keith E. Chesney and Mertie E. Chesney,
Fruitland, Idaho

Application July 10, 1950, Serial No. 172,820

10 Claims. (Cl. 228—64)

1 This invention comprises novel and useful improvements in a hydraulic hoist for ladders and more specifically pertains to a hoisting device specifically adapted for use with ladders, scaffolding and the like, for longitudinally extending the same to effect a secure fastening of the opposite ends of the ladder.

The principal object of this invention is to provide a device which shall be capable of vertically extending a ladder to securely wedge or fasten the upper and lower ends of the same against accidental displacement.

A further object of the invention is to provide a hoisting attachment in conformity with the preceding object which shall be adapted to securely engage one end of the side rails of a ladder for elevating the same and wedge the upper ends of the ladder against an anchoring surface.

Yet another object of the invention is to provide a hoisting device as set forth in the foregoing objects which shall be of inexpensive and simple construction, may be readily operated by manual means; and which shall form during its operation, a part of the ladder to which the same is attached.

These, together with various ancillary objects and features of the invention, which will later become apparent as the following description proceeds, are attained by the present invention, a preferred embodiment of which has been illustrated, by way of example only, in the accompanying drawings, wherein:

Figure 1 is a perspective view, parts being broken away, showing the manner in which the principles of the present invention may be applied to a conventional ladder for adapting the same for vertical adjustment; and

Figure 2 is a front elevational view of the construction shown in Figure 1, parts of the hoisting device being broken away and shown in vertical section.

Referring now more specifically to the accompanying drawings, wherein like numerals designate similar parts throughout the various views, it will be seen that the numeral 10 indicates generally a conventional form of ladder to which the principles of this invention have been applied.

This ladder includes a customary pair of side rails 12 and 14, between which are secured the usual rungs 16 of any conventional design.

It is to the ladder 10 that the novel hoist forming the subject of this invention and indicated generally by the numeral 18 is to be applied.

Conveniently, the hoist comprises a pair of parallel, vertically disposed members 20 which

are of hollow or tubular construction and are open at their upper and lower ends, being provided intermediate their ends with horizontally disposed partitions 22 which thus divide the interior of the members 20 into an upper cylinder or socket 24 and a lower chamber or cylinder 26. The two members 20 are preferably rigidly secured together as by a horizontal, integral brace rod 28, which thus serves to rigidly hold the two members 20 in properly spaced relation.

The upper portions of the members 20, having the above-mentioned sockets or chambers 24, constitute seating members for receiving the lower ends of the side rails 12 of the ladder 10 in a detachable manner as will now be readily understood. It is, of course, evident that if desired some means such as a bolt, screw or the like could be provided for firmly securing the lower ends of the side rails 12 in the sockets 24 of the seating members 20. When positioned, as shown in Figure 2, it is intended that the brace 28 shall be substantially identical with and constitute a supplemental rung 16 for the ladder 10 as extended by the device 18.

2 A pair of support legs 30, rigidly attached to each other intermediate their ends as by a brace rod 32, are provided with pistons 34 at their upper extremities, which are slidably receivable in the chambers or cylinders 26. These pistons are retained in the chambers and prevented from removal therefrom by a plate 36 which constitutes a mounting base for the hoist and also constitutes a closure for the open lower ends of the hydraulic cylinders or chambers 26, this plate being removably secured to the cylinders as by fastening bolts or the like 38. Mounted upon the plate or base 36 in any desired manner, is a conventional form of hydraulic pump indicated by the numeral 40 and having an operating handle 42 for manual operation. Associated with the pump 40 and likewise mounted upon the base or plate 36, is a combined hydraulic fluid reservoir 44 and valve mechanism, the latter being conveniently controlled by the conventional form of control knob 46. Suitable conduits 48 connect the pump assembly with the pressure chambers 26.

A pair of caps 50 are detachably positioned upon the upper ends of the side rails 12 of the ladder, the same being provided with suitable anchoring means such as the spikes 52.

In operation, the ladder 10 with the hoisting device 18 applied thereto as shown, is positioned with the support legs 30 resting against one supporting surface, and by manually operating the pump 40, the pressure fluid discharged therefrom

through the lines 48 into the pressure chambers 26 will move the support leg assembly outwardly of the members 20 and thus relatively extend the distance between the outer ends of the support legs and the anchor members 40 at the other end of the ladder. Thus, the extending of the ladder assembly will securely wedge the same by means of the anchor members 52 and the support legs 30 into a firm and rigidly held position, whereby the ease and safety of use of the ladder will be greatly enhanced, and the ladder may be securely held as for scaffolding and the like.

By manipulating the control knob 46, the control valve, not shown, will be so operated as to permit the return of the pressure fluid from the chambers 26 back into the reservoir 44, thereby permitting the leg assembly to be collapsed into the members 20 to permit removal of the ladder.

As will be readily understood, the braces 28 and 32 are so positioned as to constitute supplemental rungs for the entire ladder assembly, and if desired these two braces together with the plate 36 could be made laterally extensible to adapt the device to accommodate different widths of ladders.

From the foregoing, the construction and operation of the invention will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A ladder attachment comprising a base, a pair of spaced seat members mounted on said base and having means for receiving and supporting the ends of a pair of ladder rails, a pair of support legs mounted on said base and extending on the opposite side thereof from said seat members, a hydraulic hoist for causing sliding movement between said seat members and said support legs, and a control valve for said hoist.

2. A ladder attachment comprising a base, a pair of spaced seat members mounted on said base and having means for receiving and supporting the ends of a pair of ladder rails, a pair of support legs mounted on said base and extending on the opposite side thereof from said seat members, a hydraulic hoist for causing sliding movement between said seat members and said support legs, a control valve for said hoist, a lateral brace rigidly connecting said seat members.

3. A ladder attachment comprising a base, a pair of spaced seat members mounted on said base and having means for receiving and supporting the ends of a pair of ladder rails, a pair of support legs mounted on said base and extending on the opposite side thereof from said seat members, a hydraulic hoist for causing sliding movement between said seat members and said support legs, a valve controlling said hoist, a lateral brace rigidly connecting said seat members, said brace being parallel to the ladder rungs and having the same space from the adjacent ladder rung to form a continuation of said rungs.

4. A ladder hoist comprising a base, a pair of spaced seat members mounted on said base and having means for receiving and supporting the

ends of a pair of ladder rails, a pair of support legs mounted on said base and extending on the opposite side thereof from said seat members, hydraulic means for extending said support legs with respect to said seat members, a lateral brace connecting said support legs, a control valve for said hydraulic means.

5. A ladder hoist comprising a base, a pair of spaced seat members mounted on said base and having means for receiving and supporting the ends of a pair of ladder rails, a pair of support legs mounted on said base and extending on the opposite side thereof from said seat members, hydraulic means for causing sliding movement between said seat members and said support legs, a valve controlling said hydraulic means, lateral braces respectively rigidly connecting said seat members and said support legs, said braces comprising supplemental rungs at one end of a ladder, anchoring means at the other ends of said ladder rails, said sliding movement pressing said anchoring means into anchoring position.

6. A ladder hoist comprising a base, a pair of spaced seat members mounted on said base and having means for receiving and supporting the ends of a pair of ladder rails, a pair of support legs mounted on said base and extending on the opposite side thereof from said seat members, said base having fluid pressure cylinders, said support legs having pistons slidable in said cylinders, means for supplying fluid pressure to said cylinders for causing sliding movement between said seat members and said support legs to extend the support legs with respect to said base, and a valve for releasing the fluid pressure from said cylinders.

7. A ladder hoist comprising a pair of parallel cylinders, a socket mounted on the upper end of each cylinder for receiving and supporting a ladder rail therein, each cylinder below said socket having a chamber, a support leg slidable in each chamber and extending below said cylinders, a plate extending between said cylinders and closing the lower chambers and retaining said support legs therein, means for forcing fluid into said chamber for causing sliding movement of said support legs in said chambers, and a fluid release valve for said cylinders.

8. A ladder hoist comprising a pair of parallel cylinders, a socket rigidly mounted on the upper end of each cylinder for receiving and supporting a ladder rail therein, each cylinder below said socket having a chamber, a support leg slidable in each chamber and extending below said cylinders, a plate extending between said cylinders and closing the lower chambers and retaining said support legs therein, a fluid pressure pump mounted on said plate and operatively connected to said chambers for delivering fluid into said chambers for causing sliding movement of said support legs in said chambers, and a valve for relieving the fluid pressure in said cylinders.

9. A ladder hoist comprising a pair of parallel cylinders, a socket integral with the upper end of each cylinder for receiving and supporting a ladder rail therein, each cylinder below said socket having a chamber, a support leg slidable in each chamber and extending below said cylinders, a plate extending between said cylinders and closing the lower chambers and retaining said support legs therein, means for delivering fluid under pressure into said chambers for causing reciprocating movement of said support legs in said chambers, a fluid release

valve for releasing the fluid pressure in said cylinders, braces respectively rigidly connecting said sockets and said support legs and forming supplemental rungs for a ladder.

10. A ladder having side rails and rungs secured therebetween, a ladder hoist comprising a base, a pair of seat members mounted thereon for receiving one end of said rails, a pair of fluid cylinders on the opposite sides of said base from said members, pistons slidable in said cylinders, support legs mounted on said pistons and extending beyond said cylinders, a plate extending between said cylinders and retaining said pistons therein, a fluid reservoir, connections from said reservoir to said cylinders and pump means for forcing fluid from said reservoir into said cylinders for extending said support legs,

a control valve controlling the return flow of fluid from said cylinders to said reservoir.
